(57) **CLAIM**

The ornamental design for a lamp, as shown and described.

DESCRIPTION

FIG. 1 is a perspective view of a first embodiment of a lamp showing our new design;

FIG. 2 is another perspective view showing our design in a second position;

FIG. 3 is a bottom view of FIG. 1, the other end not shown is a mirror image;

FIG. 4 is a bottom view of FIG. 2, the other end not shown is a mirror image;

FIG. 5 is a side view of FIG. 1, the other end not shown is a mirror image;

FIG. 6 is a side view of FIG. 2, the other end not shown is a mirror image;

FIG. 7 is an end view of FIG. 1;

FIG. 8 is an end view of FIG. 2;

FIG. 9 is a perspective view of a second embodiment thereof;

FIG. 10 is a perspective view showing the second embodiment in a second position;

FIG. 11 is a bottom view of FIG. 9, the other end not shown is a mirror image;

FIG. 12 is a bottom view of FIG. 10, the other end not shown is a mirror image;

FIG. 13 is a side view of FIG. 9, the other end not shown is a mirror image;

FIG. 14 is a side view of FIG. 10, the other end not shown is a mirror image;

FIG. 15 is an end view of FIG. 9;

FIG. 16 is an end view of FIG. 10;

FIG. 17 is a perspective view of a third embodiment thereof;

FIG. 18 is a perspective view showing the third embodiment in a second position;

FIG. 19 is a bottom view of FIG. 17, the other end not shown is a mirror image;

FIG. 20 is a bottom view of FIG. 18, the other end not shown is a mirror image;

FIG. 21 is a side view of FIG. 17, the other end not shown is a mirror image;

FIG. 22 is a side view of FIG. 18, the other end not shown is a mirror image;

FIG. 23 is an end view of FIG. 17;

FIG. 24 is an end view of FIG. 18;

FIG. 25 is a perspective view of a fourth embodiment thereof;

FIG. 26 is a perspective view showing the fourth embodiment in a second position;

FIG. 27 is a bottom view of FIG. 25, the other end not shown is a mirror image;

FIG. 28 is a bottom view of FIG. 26, the other end not shown is a mirror image;

FIG. 29 is a side view of FIG. 25, the other end not shown is a mirror image;

FIG. 30 is a side view of FIG. 26, the other end not shown is a mirror image;

FIG. 31 is an end view of FIG. 25;

FIG. 32 is an end view of FIG. 26; and,

FIG. 33 is a side view of our design separate from the lamp housing.

The jagged tines of FIGS. 1–32 indicate indeterminate length. The broken lines immediately adjacent the shaded areas represent the bounds of the claimed design while all other broken lines are environmental and are for illustrative purposes only; the broken lines form no part of the claimed design.
